Specification for Design.

Patented Jan. 24, 1922.

Application filed October 26, 1920. Serial No. 419,738. Term of patent 14 years.

To all whom it may concern:

Be it known that we, ERICK V. LINDQUIST and CHARLES A. LINDQUIST, citizens of the United States of America, and resident of Des Moines, Polk County, Iowa, and New Auburn, Chippewa County, Wisconsin, respectively, have invented a new, original, and ornamental Design for a Garment Stud, of which the following is a specification, reference being had to the accompanying drawing, forming a part thereof.

The object of this invention is to provide an ornamental design for a garment stud.

Our invention consists in the ornamental design for a garment stud hereinafter claimed and illustrated by the accompanying drawing.

The figure is a perspective of a garment stud embodying our new design.

We claim as our invention—

The ornamental design for a garment stud, as shown.

Signed at Bloomer, in the county of Chippewa and State of Wisconsin, this 28th day of September, 1920.
